ATTORNEY.

UNITED STATES PATENT OFFICE.

AUGUST H. PAPE, OF KENTFIELD, CALIFORNIA.

CONCRETE BUILDING FORM.

Application filed December 5, 1927. Serial No. 237,672.

This invention relates to a sectional, take-down metal form or mold for use in setting up concrete pillars, columns, and the like.

An object of the invention is to provide a metal form or mold which may be used over and over, and which may be set up in such a manner as to save time and labor as compared to wooden and other types of forms.

Another object of the invention is to provide a metallic concrete form that may readily be adjusted to occupy slightly greater or lesser dimensions to facilitate the building of concrete pillars or columns of different dimensions without the necessity of providing special forms therefor.

The invention further contemplates a form that will be strong and durable. Convenience of arrangement of parts, lightness, strength and inexpense of manufacture are further desiderata that have been borne in mind in the production and development of this invention.

With these and other objects in view, which will more readily appear as the nature of the invention is better understood, the same consists in the novel construction, combination and arrangement of parts which will hereinafter be more fully described, illustrated and claimed.

The essential features of the invention involved in the carrying out of the objects indicated are susceptible to modification, but a preferred embodiment of the invention is shown in the accompanying drawings, in which:

Fig. 1, is a fragmentary side view of a plurality of forms embodying the principles of my invention, showing the same in assembled relation; which assembled structure serves to form the mold for a square pillar or column.

Fig. 2 is an enlarged detail view of one of the corner fastenings employed in connection with my invention, and its mode of connection.

Fig. 3 is a top plan view of the construction shown in Fig. 1.

Fig. 4 is an enlarged detail view of the corner fastening employed in connection with my invention, and its mode of attachment in a modified arrangement of the column.

Fig. 5 is a top plan view of a modified form of the invention showing a form that is adapted to be used in connection with the

building of a polygonal or circular pillar or post.

Fig. 6 is a view similar to Fig. 4, showing the parts in a slightly adjusted position with respect to the position shown in this former figure.

Fig. 7 is an end elevation of one of the channel form members.

Referring to the accompanying drawings wherein similar reference characters designate similar parts throughout, the various figures described above adequately illustrate my invention and the following detailed description is commensurate with the above mentioned drawings in enabling an artisan to construct and assemble the constituent parts of the same.

Each concrete pillar or column that is constructed involves in its general mold organization, a plurality of superimposed forms 10. Referring to Figs. 1, 2, 3, 4 and 6, each of these forms comprises a plurality of angularly disposed channel pieces 11 having flanges 12 and 13 along the longitudinal edges thereof. At one end of each channel piece these flanges 12 and 13 terminate flush with the edge 80 of the same and abut against the medial portion of the adjacent angle piece. These ends of the channel pieces excepting the flanges, are bent right angularly to provide reinforcing flanges 14. Each flange 12 and 13 has extending along the center thereof a row of spaced bolt apertures 13'. Bolted to the channel pieces 11 at the abutting portions thereof, are a plurality of corner fastening plates 15. Each corner fastening plate is comprised of a triangular strip of sheet material, having a row of bolt holes 16 extending along an edge 17 thereof, and a plurality of rows of bolt holes 18 and 19 extending along an edge 20 thereof. Suitable bolts 21 serve to hold the parts in assembled position. Each form, when assembled, forms a compact, unitary symmetrical mold unit that is well adapted to perform the services required of it.

It is to be particularly noted that in Figs. 1, 2, 3 and 4, the angular corner fastening plates 15 each have the edge 20 thereof slightly projected beyond the plane of the channel pieces 11. This is accomplished by employing the bolt holes 18 in connecting 105 the corner fastening plates to the flanges 12 and 13. In Fig. 6, a different adjustment is obtained by using the bolt holes 19 in place of

the holes 18. It will be seen that when the holes 19 are utilized the edge 20 of the corner fastening plates lie substantially flush with the plane of the channel pieces 11, and 5 a slightly smaller form is obtained.

In Fig. 2, the channel pieces are reversed to bring the beveled ends 25 of the flanges and the angularly extending lip 25' into position so that said lip abuts against the mediate 10 portion of its companion channel piece. This beveled end facilitates the formation of octagonal forms as will be later described, and when used to provide a square form as shown in Fig. 2, provides a beveled corner on the 15 finished structure. The angularly extending lip 25' serves to reinforce the channel member as does the flange 14, and prevents buckling of the form members.

These beveled edges may be utilized in the 20 preferred construction to obtain a different adjustment of the parts if desired. By reversing the channel pieces so that these beveled edges abut against the medial portions, a slightly different adjustment is obtained.

25 In the modified form of the invention wherein a polygonal or a round pillar or post is obtained, the beveled edges are a necessary part of the construction. In this 30 form of the invention the channel pieces 11 are arranged at an angle to each other with the beveled edges 25 abutting against the medial portion of adjacent pieces to constitute a polygonal shaped form. In order to 35 insure the proper adjustment and attachment of the channel pieces to each other, the corner fastenings 15 are secured along the acute edges of the same to the flanges 12 and 13 of the angle pieces 15, and thus a compact, 40 adjustable unitary form is obtained that will be well adapted in the forming of polygonal or circular concrete columns.

I am aware that some changes may be made in the general arrangements and combinations of the several parts of the device, 45 as well as in the details of the construction thereof without departing from the scope of the present invention as set forth in the foregoing specification, and as defined in the following claims. Hence I do not desire to limit my invention to the exact arrangements and combinations of the said device and parts as described in the above specification, nor do I confine myself to the exact details of the constructions illustrated in the 50 said drawings. Only in so far as I have particularly pointed out my invention in the appended claims do I desire to limit myself.

I claim:

1. A metal form for use in erecting concrete structures, comprising a plurality of channel shaped metal form members arranged so as to engage one another, the flanges of said form members having openings therein, a plurality of fastening plates adapted to 60 overlie the flanges of said members where

said members abut one another, which fastening plates are provided with openings adapted to register with openings in the flanges, and detachable fastening elements inserted through certain aligned openings of 70 said flanges and plates, said plates having a plurality of rows of openings, the openings of either rows of which being adapted to register with the openings in the flanges.

2. A form for use in setting up concrete 75 structures comprising a plurality of metallic channel shaped form members adapted to engage with one another and each having in the flanges thereof a plurality of openings, each of said channel members having angularly extending vertical flanges at the ends 80 thereof, the horizontal flanges of the channel pieces being beveled at certain ends of the channel pieces, attaching plates having openings therein adapted to register with the openings in the flanges, and fastening elements inserted through the registering openings of the flanges and plates to hold the form members together.

3. A form for use in erecting concrete 90 structures comprising a plurality of channel shaped metallic form members having openings in the flanges thereof and which form members are adapted to engage one another to provide a mold or form, a plurality of 95 attaching plates adapted to lie upon the flanges of the channel members where said members abut one another, said attaching plates having rows of openings therein with the rows extending angularly with relation 100 to one another and the openings adapted to be brought into registration with the openings of the flanges, and fastening elements extending through aligned openings of the plates and flanges for securing the form members together.

4. A form for use in erecting concrete structures comprising a plurality of channel shaped form members arranged to engage one another and having in the flanges thereof along their upper and lower edges a plurality of openings, certain ends of said channel members being beveled, a plurality of substantially triangular attaching plates adapted to engage the flanges of the channel members adjacent the points where said channel members abut one another, which attaching plates are provided with rows of openings extending angularly to one another, said last named openings being adapted to register with the openings of the flanges, and removable fastening elements extending through certain aligned openings of the plates and fastenings.

5. A form for use in setting up concrete 125 structures comprising a plurality of channel shaped form members arranged in upright position in substantially the same horizontal plane, with one end of each channel member abutting another of the channel members at a point between the ends of the second 130

named channel members to thereby provide a substantially square or rectangular mold, said channel members having rows of openings in the flanges thereof, a plurality of attaching plates engaging the flanges on upper and lower sides of the form members at the points where the said members engage one another, which attaching plates are provided with angularly related rows of openings adapted to register with openings in the flanges, certain edges of the attaching plates being substantially flush with the mold faces of the form members, and removable fastening elements inserted through certain registering openings of the plates and flanges for securing the form members together.

6. A form for use in setting up concrete structures comprising a plurality of channel shaped form members arranged in upright position in substantially the same horizontal plane, with one end of each channel member abutting another of the channel members at

a point between the ends of the second named channel members to thereby provide a substantially square or rectangular mold, said channel members having rows of openings in the flanges thereof, a plurality of attaching plates engaging the flanges on upper and lower sides of the form members at the points where the said members engage one another, which attaching plates are provided with angularly related rows of openings adapted to register with openings in the flanges, certain edges of the attaching plates being substantially flush with the mold faces of the form members, and removable fastening elements inserted through certain registering openings of the plates and flanges for securing the form members together, there being an additional row of openings in the attaching plates, which additional row extends parallel to one of the first named rows in spaced relation thereto.

AUGUST H. PAPE.
